UNITED STATES PATENT OFFICE

143,724

DESIGN FOR A HAND TOOL FOR GARDENING

John J. Getgey, Cincinnati, Ohio, assignor to Empire Products, Inc., Cincinnati, Ohio, a corporation of Ohio

Application April 27, 1945, Serial No. 119,263

Term of patent 3½ years

(Cl. D35—2)

To all whom it may concern:

Be it known that I, John J. Getgey, a citizen of the United States, residing at Cincinnati, in the county of Hamilton, and State of Ohio, have invented a new, original, and ornamental Design for a Hand Tool for Gardening, of which the following is a specification, reference being had to the accompanying drawing, forming a part thereof.

for gardening showing my new design.

Figure 2 is a side elevational view thereof.

I claim:

The ornamental design for a hand tool for gardening, substantially as shown.

JOHN J. GETGEY.
